UNITED STATES PATENT OFFICE.

WILLIAM P. WITHEROW, OF PITTSBURGH, PENNSYLVANIA, ASSIGNOR TO WITHEROW STEEL COMPANY, OF NEVILLE ISLAND, PENNSYLVANIA, A CORPORATION OF PENNSYLVANIA.

DIE ROLLING.

Application filed August 1, 1923. Serial No. 655,061.

To all whom it may concern:

Be it known that I, WILLIAM P. WITHEROW, a citizen of the United States, residing at Pittsburgh, Allegheny County, Pennsylvania, have invented a new and useful Improvement in Die Rolling, of which the following is a full, clear, and exact description.

The present invention relates broadly to metal rolling, and more particularly to the art of die rolling, in which accuracy and uniformity in the dimensions of the successive blanks or articles produced by the die rolls is important.

While the art of die rolling lends itself admirably to the production of enormous tonnage of blanks or articles due to the rapidity with which metal can be shaped by the rolls, considerable difficulty has heretofore been experienced, due to the fact that at different times, either on the same or different mills, blanks or articles of varying lengths have been formed. This has made it necessary to perform at least one additional operation on the blanks or articles so produced, in order to bring them to the required dimensions.

By almost constant study of the art of die rolling, I have been led to the belief that variations in length of the blanks produced may be attributed to a considerable extent to the action of the die rolls on the metal being worked. If the amount of work performed on any given length of metal stock is varied by varying the amount of roll slip, there is a corresponding variation in the length of the resulting article. This is somewhat contrary to the metal working art broadly in which variations in length are produced by increasing the temperature for increased length and decreasing the temperature for decreased lengths. In the metal rolling art broadly, the results obtained by variations of temperature can apparently be explained by the variation in the ease with which the metal may be reduced in accordance with different temperatures and also by reason of the fact that the number of passes may be varied so that certain results can be obtained.

As disclosed in my United States Patent No. 1,516,069 of November 18, 1924, it is possible to vary the action of the rolls, and correspondingly control the length of blank produced, by certain temperature changes in the metal being worked. Also, as disclosed in my copending application, Serial No. 655,060 filed August 1, 1923 similar results may be produced either with or without temperature changes by changing the speed at which the die rolls are operated. I believe that in the latter case, the operation of the rolls at a higher speed produces blanks having a less length than would be produced if the rolls were operated at normal speed, by reason of the fact that the roll slip changes in some definite proportion to the roll speed.

In accordance with the present invention, I produce variations from the normal lengths of blanks in still another way. This invention has several advantageous features, among which may be mentioned the production of smoother blanks by reason of the elimination of scale from the billets being die rolled and also the ease of control of the lengths of the blanks produced.

In the accompanying figure of drawings, I have shown more or less diagrammatically for purposes of illustration only, one embodiment of the present invention, it being understood that changes in the construction and operation may be made without departing from the spirit of the invention or the scope of my broader claims.

In the drawings, I have illustrated a stand of rolls comprising an upper roll 2 and a lower roll 3, adapted to be driven in any desired manner in the direction indicated by arrows. Positioned at the entering side of the rolls, there is provided a nozzle or plurality of nozzles 4, adapted to direct a stream of fluid of suitable character against some or all of the surfaces of the billet being rolled, the fluid being initially directed against the billet in a direction in opposition to its travel through the rolls. While I have found that either air, steam or water may be effectively used for this purpose, I have preferably utilized water due to its greater

cooling properties and due to the ease of obtaining a suitable supply under pressure. The fluid discharge against the billet not only effectively removes any loose scale from the surface thereof, but also produces a reduction in the temperature. As clearly pointed out in my patent, referred to, the greater the reduction in the temperature, the longer, comparatively, is the blank produced by the die rolls.

In obtaining the full benefits of the present invention, the metal may all be initially heated to a temperature somewhat higher than that which would normally be required. This facilitates the initial treatment of the billet in the roughing passes, and makes it possible to supply a leader of the required shape and section to the die rolls at a comparatively high temperature. If this leader at this temperature when rolled produces blanks which are too short, it is only necessary to increase the supply of cooling fluid directed against the leader. In this manner, it is possible to easily and quickly produce changes in the lengths of blanks produced by the die rolls, whereby the desired uniformity is insured.

It will be obvious to those skilled in the art that the application of fluid to the metal being rolled may be utilized for effecting the desired results, or the result may be partially obtained by varying the amount of fluid or its temperature and the remaining compensation in the length effected by a variation in the roll speed. Thus, for example, if the resulting blank produced by the rolls is too short, the temperature of the entering leader may be reduced by the application of the proper quantity of fluid at the proper temperature, or the necessary increase in the length may be obtained partially by the application of a greater amount of fluid, or fluid at a lower temperature; and by decreasing the roll speed. To produce a shorter blank, the opposite steps will be carried out.

The variations in roll speed and temperature should also preferably bear a definite relation to the reduction which is being effected in the metal by the die rolls. In other words, as the per cent of reduction increases, an increase in roll speed, either with or without a decrease in the amount of cooling fluid, will produce a shorter blank than would be produced under the same conditions if the per cent of reduction was less.

It may also be that the length of the blank produced is dependent upon the removal of scale from the leader being die rolled. Thus, as the temperature of the leader is reduced by the application of a greater volume of fluid under pressure, the amount of scale is accordingly reduced, and therefore, there is presented a surface which may be effectively gripped by the die rolls.

The advantages of the present invention arise from the provision of a method for quickly and easily varying the comparative lengths of blanks produced by die rolls, whereby uniformity in successive blanks is insured.

I claim:

1. In the method of die rolling blanks of a desired length from leaders, the steps consisting in passing a leader through the die rolls and directing a cooling fluid thereagainst, and thereafter passing other leaders through said die rolls and varying the amount of cooling fluid directed thereagainst to produce blanks varying in length from those produced from the first mentioned leader, substantially as described. 75

2. In the method of die rolling blanks of a desired length from leaders, the steps consisting in passing a leader through the die rolls and directing a cooling fluid thereagainst, and thereafter passing other leaders through the same die rolls and varying the amount of cooling fluid directed thereagainst to produce blanks varying in length from 80 those produced from the first mentioned leader, substantially as described. 85

3. In the method of die rolling blanks of a desired length from leaders, the steps consisting in passing a leader through the die rolls and directing a cooling fluid thereagainst, and thereafter passing other leaders through the same die rolls but with an increased amount of cooling fluid directed thereagainst to produce blanks longer than 90 those produced from the first mentioned leader, substantially as described. 95

4. In the method of die rolling blanks of a desired length from leaders, the steps consisting in passing a leader through the die rolls and directing a cooling fluid thereagainst, and thereafter passing other leaders through the same die rolls but with a decreased amount of cooling fluid directed thereagainst so as to produce blanks shorter than those produced from the first mentioned leader, substantially as described. 100 105

5. In the method of die rolling blanks of a desired length from leaders, the steps consisting in passing a leader through the die rolls and directing a cooling fluid thereagainst, and thereafter passing other leaders through the same die rolls and varying the amount of cooling fluid directed thereagainst to produce blanks varying in length from those produced from the first mentioned leader, at the same time varying the roll speed of the die rolls, substantially as described. 115 120

6. In the method of die rolling blanks of a desired length from leaders, the steps consisting in passing a leader through the 125 130

die rolls and directing a cooling fluid thereagainst, and thereafter passing other leaders through the same die rolls and varying the amount of cooling fluid directed thereagainst to produce blanks varying in length from those produced from the first mentioned leader, at the same time varying the roll speed of the die rolls, both of said variations being in accordance with the percentage of reduction to be effected by the die rolls, substantially as described.

In testimony whereof I have hereunto set my hand.

WILLIAM P. WITHEROW.
